(57) **CLAIM**

The ornamental design for a “form insert for forming a joint in coping,” as shown and described.

DESCRIPTION

FIG. 1 is a perspective view of a form insert for forming a joint coping, showing my new design;
FIG. 2 is a front elevational view thereof;
FIG. 3 is a rear elevational view thereof;
FIG. 4 is a left side elevational view thereof, the right side elevational view being a mirror image thereof;
FIG. 5 is a top plan view thereof; and,
FIG. 6 is a bottom plan view thereof.
